UNITED STATES PATENT OFFICE

123,510

DESIGN FOR A DUSTPAN

Frederick C. Prentice, Great Bend, Pa., assignor
of one-half to Perry W. Heath, Great Bend,
Pa.

Application May 8, 1940, Serial No. 92,226

Term of patent 14 years

To all whom it may concern:

Be it known that I, Frederick C. Prentice, a citizen of the United States, residing at Great Bend, in the county of Susquehanna and State of Pennsylvania, have invented a new, original, and ornamental Design for a Dustpan, of which the following is a specification, reference being had to the accompanying drawing, forming part thereof.

Figure 1 is a view in front elevation of a dustpan, showing my new design.

Figure 2 is a side elevational view thereof.

Figure 3 is a top plan view thereof.

Figure 4 is a bottom plan view thereof.

I claim:

The ornamental design for a dustpan, as shown.

FREDERICK C. PRENTICE.
